DESIGN FOR A FRANKFURTER COOKER

Benjamin A. Busey, York, and Robert B. Hartzler, Cly, Pa.

Application October 24, 1938, Serial No. 80,693

Term of patent 3½ years

To all whom it may concern:

Be it known that we, Benjamin A. Busey and Robert B. Hartzler, citizens of the United States, residing, respectively, at York and Cly, in the county of York and State of Pennsylvania, have invented a new, original, and ornamental Design for Frankfurter Cookers, of which the following is a specification, reference being had to the accompanying drawing, forming part thereof.

In the drawing:

We claim:

The ornamental design for a frankfurter cooker, as shown.

R. B. HARTZLER.
